ATTORNEY.

UNITED STATES PATENT OFFICE.

MATTHEW MARES, OF RACINE, WISCONSIN.

PLOW.

Application filed April 20, 1923. Serial No. 633,430.

This invention relates to plows.

In plows heretofore constructed the plow beam is ordinarily disposed substantially within the plane of the land side so that the draft line is offset with respect to the resultant line of plow resistance. This unbalanced condition causes a heavy side thrust which, particularly in the case of hand plows, results in an objectionable zigzag action on the part of the plow.

One object of the present invention is the provision of a better balanced plow, whereby this objectionable feature may be overcome.

Another object is the provision of a plow of increased strength and rigidity in which the mold board, particularly, is securely held against yielding.

Another object is the provision of an adjustable mounting for the mold board.

Another object is the provision of a plow share which will effect a better and cleaner cut without requiring frequent grinding or replacement of worn parts.

Other objects and advantages will appear from the following description of an illustrative embodiment of the present invention.

In the drawings:

Figure 1 is a plan view of a plow constructed in accordance with the present invention.

Figure 2 is a side elevation of the land side of the plow.

Figure 3 is a horizontal section taken substantially on the line 3—3 of Figure 2.

Figure 4 is a sectional view on a larger scale taken substantially on the line 4—4 of Figure 3.

The plow illustrated comprises a rigid inside frame or frog 10 in the form of a casting having two integral wings 11 and 12. Wing 11 lies substantially in a vertical plane and constitutes a rigid support for the land side 13, while wing 12 extends beneath the plow point 14 and plow share plate 15 and is appropriately curved to conform in general with the mold board 16 supported thereby. The two wings merge in a relatively sharp corner 17 and at the upper ends thereof are rigidly connected by an integral web or plate 18 horizontally disposed and constituting an appropriate seat for one end of a

plow beam 19. The plow beam is rigidly clamped to this seat by means of a bracket plate 20 suitably fashioned to partially embrace the plow beam and secured to the web 18 by appropriate nut and bolt connections 21.

From an inspection of Figure 1 it will be noted that the plow beam is laterally disposed with respect to the land side of the plow toward the center of gravity of the plow. As above pointed out, this arrangement of the plow beam is particularly advantageous in that the line of draft is thus made to more nearly coincide with the resultant of plow resistance, thus avoiding the tremendous side thrust and consequent zigzag action characteristic of plows of present well known construction.

The mold board 16 is curved in the usual manner and is disposed in a depression 23 in the face of the wing 12 of the frog so that its exposed surface is substantially flush with the exposed surface of the plow share plate 15. The lower edges 24 of the mold board 16 thus abut the shoulder 25 formed by the depression 23. At its forward end the mold board extends over the corner 17 of the frog and is provided with an integral flange 24' which bears against the face of the wing 11 to retain the mold board against lengthwise movement. Provision is preferably made for permitting a slight rocking adjustment of the mold board about its lower edges. In this instance, this adjustment is controlled by a cam 25' rotatably mounted upon the face of the wing 11 and bearing at its periphery against the edge of the flange 24'. The cam is supported upon and held in any position of adjustment by an appropriate clamp screw 26 extending therethrough and into the wing 11. An integral lug 27 extending from the under face of the mold board and through an appropriate slot in the wing 12 of the frog is adjustably connected to the wing 11 by bolt connections 28. The rear end of the mold board is also adjustably secured to the extension 29 of the wing 12 by means of bolt connections 30 associated with lugs 31 and 32 on the extension 29 and mold board, respectively. In this instance, the bolts 30 and lugs 31 serve as a means for

connecting one of the plow handles 33. Thus it will be understood that after loosening the bolts 28 and 30 the mold board may be rocked about its lower edge to the desired 5 position of adjustment by adjusting the cam 25 and that by again tightening the bolts 28 and 30 they assist the cam in rigidly securing the mold board against yielding. The mold board may be made of usual material, 10 such as cast steel or iron, but in some instances I prefer to coat the mold board with a layer of non-oxidizing material, such as porcelain, to prevent rusting.

The plow point 14 and plow share 15 are 15 preferably separable, each being secured against the face of the wing 12 of the frog. The land side 13 is bolted against the face of the wing 11 of the frog, its forward edge 13' being beveled and interlocked with an 20 appropriate groove in the under face of the plow point substantially in the manner shown and described in my prior Patent No. 1,140,275, issued May 18, 1915.

The plow share comprises a plate 15 rigidly secured against the face of the wing 12 of the frog by means of screws 34 threaded into depending lugs 35, seated in openings 36 in the wing 12 so as to provide an interlocking engagement therewith. The plate 30 15 carries a series of rotatable cutting disks 37 so disposed that the beveled cutting edges thereof overhang the edge 38 of the plate and constitute the cutting edge of the plow share. As shown, particularly in Figure 4, 35 each disk 37 is journaled upon the round shank 39 of a bolt 40, the bolt being secured in an eccentric 41 adjustably mounted in an appropriate socket 42 formed in the under face of the plate 15. Each eccentric is locked 40 in any desired position of adjustment by means of a key 43 seated in a socket 44 in the under face of the plate 15 and engageable with the serrated edge 45 of the eccentric. In use, the peripheries of the several disks 45 are preferably retained in slight overlapping relation. As they become worn, they may be adjusted toward each other by withdrawing the key 43 and rotating the eccentric 41 until the desired position is attained, 50 in which position the eccentric is again locked by the reinsertion of the key.

In order to keep the edges of the disks in a sharp condition, a suitable abrasive element 46 may be provided in a socket 47 in the plate 15 where it is maintained in contact with the cutting edge of the disk. It is understood, of course, that during the operation of the plow the reaction of the soil against the disks causes them to rotate continuously in one direction. This rotation of each disk against its abrasive element maintains the disks in a sharp condition and thus insures a clean cutting of the soil and all roots encountered.

65 The plow share is also preferably pro-

vided with a series of conduits or ducts 48, each leading to a point beneath a disk, through which a powder or fluid may be distributed for killing weeds, beetles or other vermin that might otherwise interfere with the proper growth of the crops. These conduits may be fed from any suitable source (not shown) carried by the plow.

As shown, particularly in Figures 2 and 4, a plate 49 is secured against the inner face 75 of the wing 11 of the frog and extends rearwardly therefrom substantially parallel to the land side 13. It is secured in position by bolts 50, one of which extends through an appropriate spacer lug 51 formed as an integral part of the land side 13. This plate carries a bracket 52 bolted thereto and constituting a bearing 53 for the end of a stub shaft 54 rotatably journaled therein. A roller 55, keyed to this shaft, tends to sustain the weight of the plow and to steady the plow in its course of travel. A pulley 56 is shown secured to the roller 55 which may serve as a source of power for actuating the powder distributor hereinabove referred to.

In order to further steady the plow in its course and to facilitate entry of the plow point into the earth, the point carries a vertically disposed sharp edged disk 58 countersunk in the side face thereof, so as to lie substantially within the plane of the land side. As shown, this disk projects beneath the under portion of the plow. It is secured in position by a screw 57 which, when loosened well, permits a rotative adjustment of the disk to present a sharp edge to the earth when the edge in operation has become dull or worn.

Various changes may be made in the embodiment of the invention hereinabove described, without departing from or sacrificing any of the advantages of the invention as defined in the appended claims.

I claim:

1. A plow having a plow share provided with a plurality of disks constituting the cutting edge thereof, said disks lying in the plane of the share.
2. A plow having a plow share provided with a plurality of rotatable disks constituting the cutting edge thereof, said disks lying in the plane of the share.
3. A plow having a plow share provided with a plurality of disks in overlapping relation constituting the cutting edge thereof.
4. A plow having a plow share provided with a plurality of disks, and adjustable mounting means for said disks permitting lateral adjustment thereof.
5. A plow having a plow share provided with a plurality of disks constituting a continuation thereof in the plane of the share and projecting beyond the edge thereof to provide a cutting edge therefor.

6. A plow having a plow share, a series of disks rotatably mounted thereon so as to turn about axes extending normal to and through said share, said disks having cutting edges cooperating to form the cutting edge of said share.
- 5 7. A plow having a plow share provided
- with rotatable discs thereon comprising revolving shares, and means associated with said disks to automatically sharpen them 10 when in operation.

In witness whereof, I hereunto subscribe my name this 9th day of April, 1923.

MATTHEW MARES.
